COMBINED PHONOGRAPH AND CARTRIDGE PLAYER

Falkon S. Davis, Berkeley Heights, N.J., assignor to Brother International Corporation, New York, N.Y.

Continuation-in-part of abandoned design application Ser.
No. 387,778, Aug. 13, 1973. This application Apr. 23,
1975, Ser. No. 570,665

Term of patent 14 years

Int. Cl. D14—01

U.S. Cl. D56—4 R

FIG. 1 is a top plan view of a combined phonograph and cartridge player showing my new design;

FIG. 2 is a front elevational view; and

FIG. 3 is a right side elevational view.

This is a continuation-in-part of design application Ser. No. 387,778, filed Aug. 13, 1973, abandoned.

I claim:

The ornamental design for a combined phonograph and cartridge player, substantially as shown and described.
